UNITED STATES PATENT OFFICE.

FISHER H. LIPPINCOTT, OF PHILADELPHIA, PENNSYLVANIA.

PENCIL-SHARPENER.

SPECIFICATION forming part of Letters Patent No. 724,303, dated March 31, 1903.

Application filed May 17, 1901. Serial No. 60,699. (No model.)

To all whom it may concern:

Be it known that I, FISHER H. LIPPINCOTT, a citizen of the United States, residing in Philadelphia, Pennsylvania, have invented 5 certain Improvements in Pencil-Sharpener, of which the following is a specification.

My invention relates to certain improvements in pencil-sharpener, having for its object the provision of a device for pointing the 10 lead of a pencil which while being easily applied to any holder or recess shall be simple in construction and inexpensive to manufacture.

The above objects I attain as hereinafter 15 set forth, reference being had to the accompanying drawings, in which—

Figure 1 is an enlarged vertical sectional view of an ordinary india-rubber-eraser holder, showing my improved sharpener as 20 applied to the same. Fig. 2 is a plan view of the sharpener. Fig. 3 is a transverse sectional view of the same on the line 3 3, Fig. 2. Fig. 4 is a side view, and Fig. 5 is a plan view, of the blank from which the sharpener 25 is made.

In the above drawings, A is an ordinary cylindrical metallic rubber-eraser holder commonly applied to the ends of lead-pencils. Retained in the holder by means of the corrugations a is a piece of rubber B, and a V-shaped pencil-sharpener C is placed within the holder, the edges resting upon the upper corrugations of the rubber-holder. This sharpener is stamped out of sheet metal by 35 appropriate machinery, having in it a slot c with parallel sides and being of the appearance shown in Fig. 5. It is then bent into a V shape, as shown in Fig. 3, the ends c' c' of the piece being bent back, so as to be in the 40 present instance in the same plane, although it will be understood that this construction is not necessary to my invention. The edges of said ends are preferably cut in the arc of a circle, as illustrated in the plan view of 45 Fig. 2.

Notches c² c² are formed in the edges of the sharpener, there being four in the specimen shown. As the said sharpener is made so that the distance between its edges is slightly 50 greater than the interior diameter of the rubber-holder, it is therefore retained in said holder.

In use the sharpener is placed, for example, in a holder of the form illustrated, and a pencil requiring its lead pointed is inserted in 55 the same, being given a rotary motion at the same time that it is pressed inwardly.

The sharpener, owing to the springy nature of the material from which it is made, presses upon the sides of the holder, and is thus prevented from rotating as the pencil is turned. As the lead of the pencil is pointed the powdered plumbago-dust collects in the bottom 60 of the holder, and after the sharpening is finished the holder may be turned upside down 65 and the dust shaken out, it passing through the notches c² c², provided for that purpose.

It will be understood that while I have shown my improved sharpener as applied to a cylindrical pencil or rubber holder it may 70 with equal advantage be placed in any suitably-formed recess or convenient holder of any desired shape—as, for example, in a hole or recess in a desk or drawer, drawing-board, &c.

75 I claim as my invention—

1. The combination of a holder having within it a substantially cylindrical cavity and a V-shaped pencil-sharpener therein, said sharpener having ends projecting at an angle 80 to its sides, said ends being circular in outline and constructed to be retained within the holder, substantially as described.

2. The combination of a holder, a pencil-sharpener therein having its sides set at an 85 angle to each other, a slot in said sharpener, the sides of the same being parallel to each other, the ends of the sharpener bearing upon the sides of said holder and thereby retaining the sharpener within the same, and notches 90 in said ends constructed to allow dust from sharpening a pencil to be removed from the holder, substantially as described.

3. The combination with a pencil-holder having a substantially cylindrical cavity, of 95 a pencil-sharpener having sides set at an angle to each other and projections extending at an angle from said sides, said projections being placed to engage the interior surface of the cavity in the holder, substantially as described.

4. The combination of a holder and a pencil-sharpener having side portions set at an angle to each other and constructed to fit

within said holder, said parts having in them
a parallel-sided slot and being provided with
end projections lying in substantially the
same plane with each other whereby the
sharpener is held in operative position within
the holder, substantially as described.
In testimony whereof I have signed my

name to this specification in the presence of
two subscribing witnesses.

FISHER H. LIPPINCOTT.
